WATER PUMP

John Pavlecka and Dana K. Badertscher, Detroit, Mich., assignors to Hudson Motor Car Company, Detroit, Mich., a corporation of Michigan

Application March 13, 1936, Serial No. 68,654

5 Claims. (Cl. 103—111)

This invention relates to pumps, and particularly although not exclusively, to centrifugal water pumps employed for circulating the coolant of internal combustion engines. The invention is especially applicable to water pumps of the type which is mounted on the same shaft as the fan employed for drawing air through the radiator to remove heat from the coolant. One of the principal objects of the invention is to provide new and improved means for sealing the pump against leakage of the coolant and at the same time for absorbing and taking up end thrusts of the pump and fan assembly.

Another object of this invention is to provide a novel thrust bearing within the pump, the bearing and associated parts being so arranged and constructed that any dirt from the coolant which might interfere with the bearing or the sealing means is automatically thrown out by centrifugal force and washed away by the coolant.

Another object of this invention is to provide an improved thrust bearing and sealing means for a pump of the foregoing type which are relatively simple in construction, efficient in operation to prevent leakage of the cooling liquid, and adapted to permit economies in the manufacture of the pump.

Other objects of this invention will appear in the following description and appended claims, reference being had to the accompanying drawing forming a part of this specification wherein like reference characters designate corresponding parts in the several views.

Fig. 1 is a sectional view taken through the axis of the pump showing the parts in the positions taken by them when the pump and fan are turning fast enough for the fan to pull the pump shaft forwards.

Fig. 2 is a perspective view, with parts broken away, of the rear bearing, the rear bearing supporting boss, the rear end of the shaft, the pump impeller and the sealing means.

Fig. 3 is an enlargement of the portion of Fig. 1 enclosed in the small dotted square.

Fig. 4 is a view similar to Fig. 3 but showing the parts in the positions occupied when the pump and fan are at rest or turning slowly.

Before explaining in detail the present invention it is to be understood that the invention is not limited in its application to the details of construction and arrangement of parts illustrated in the accompanying drawing, since the invention is capable of other embodiments and of being practiced or carried out in various ways.

Also it is to be understood that the phraseology or terminology employed herein is for the purpose of description and not of limitation, and it is not intended to limit the invention claimed herein beyond the requirements of the prior art.

In the preferred form of the invention, shown in the drawing, there is provided a pump comprising a pump body 1, a pump shaft 2 journalled in the body, a fan 3 and pulley 4 on the front end of the shaft, an impeller 5 on the rear end of the shaft, an impeller housing 6 enclosing the impeller, and an annular stationary shroud 7 having its rim held between the pump body and the impeller housing. The impeller 5 may be of any suitable construction provided with impeller blades 55 for circulating the water or other coolant for the engine as indicated by the arrows in Fig. 1.

The pump body 1 is a hollow casting arranged to support a front bearing bushing 8 and a rear bearing bushing 9 in alignment with each other, one at each side of a grease chamber 1a in the casting. The rear bearing bushing 9 is mounted in a boss 1b surrounded by an annular water passage communicating with the inlet passage and having an annular outlet surrounding and parallel to the rear portion of the shaft.

The front end of the shaft is pressed into a hub 10 which carries the fan 3 and pulley 4, the back of the hub 10 being flat and bearing against the front end of the front bearing bushing 8 to keep the shaft 2 from moving back. The rear end of the shaft is pressed into the impeller 5, which carries a thrust washer 11 bearing against the rear end of the rear bearing bushing 9 to keep the shaft from moving forward.

The thrust washer 11 forms part of the sealing means, and an important feature of the invention resides in the arrangement of this washer and the parts associated therewith. The front end 5a of the hub of the impeller 5 contains a deep counterbore concentric with and considerably larger in diameter than the shaft 2. The counterbore is composed of a short outer or forward cylindrical portion 5b separated from a deeper cylindrical inner or rear portion 5c of smaller diameter by a circumferential groove or channel 5d. The inner or rear wall of the groove 5d lies in a plane perpendicular to the shaft 2 so that it forms a flat annular shoulder 5e facing forward towards the mouth of the counterbore. The thrust washer 11, which is small enough to pass into the large forward portion 5b of the counterbore but too large to fit 55

into the smaller rear portion 5c of the counterbore, fits up against the shoulder 5e formed by the rear wall of the groove. Thus a force tending to move the shaft forward is transmitted 5 through the shoulder 5e on the impeller to the rear face of the thrust washer 11 and from the front face of the thrust washer to the back end of the rear bearing bushing 9.

To insure that relative rotational movement 10 occurs between the thrust washer 11 and the bearing bushing 9 instead of between the thrust washer and the impeller 5 which is not made of bearing metal and which is in contact with the washer over but a small annular area, the thrust 15 washer is provided with a pair of radial lugs or ears 11a which fit loosely into slots 5f cut in the walls 5a of the counterbore in the front end of the impeller hub. These slots 5f extend past the circumferential groove 5d against whose rear 20 side the thrust washer rests so that the lugs 11a on the thrust washer cannot bear on the ends of the slots 5f before the thrust washer 11 bears on the back wall 5e of the groove 5.

The rest of the sealing means of which the 25 thrust washer forms a part lies in back of the thrust washer 11 in the inner part 5c of the counterbore in the impeller hub. It comprises a cork ring 12 which fits around the shaft 2 up against the back of the thrust washer 11, an annular coil 30 spring 13 fitting in a groove around the cork ring 12 and which squeezes the ring onto the shaft 2, a spiral spring 14 around the shaft between the cork ring 12 and the bottom of the counterbore which pushes or presses the cork ring 12 tightly 35 against the thrust washer 11, and a thin metal washer 15 interposed between the spiral spring 14 and the cork ring 12 which evenly distributes the pressure of the spiral spring over the back face of the cork ring. A snap ring 16 in the forward part 5b of the impeller hub recess extends 40 across the slots 5f and holds the sealing means in the impeller hub counterbore during assembly of the pump.

When the pump is at rest, the spiral spring 45 14 within the recess in the hub 5a of the impeller pushes the impeller 5, the pump shaft 2, the fan 3, pulley 4 and the hub 10 back until the hub 10 of the fan bears against the front face of the front bearing bushing 8. At this time the thrust washer 50 11 is pressed up against the rear end of the rear bearing bushing 9 by the spiral spring 14 so that the slight end play allowed the pump shaft assembly appears as clearance between the back of the thrust washer 11 and the rear face 5e of the annular groove 5d in the impeller hub counterbore, as shown in Figure 4. When the pump is 55 in operation, there is a certain speed at which the forward pull of the fan will equal the pressure of the spiral spring 14 within the impeller hub recess. Below that speed the parts will have the same axial position as when the pump is not operating. Above that speed the pump shaft assembly will move forward until the shoulder 5e, formed by the rear wall of the annular groove in 60 the impeller hub counterbore, bears against the thrust washer 11 as shown in Figure 3 and the end play of the pump shaft assembly appears as clearance between the hub 10 of the fan and pulley and the front face of the front bearing bushing 8, as shown in Figure 1.

The slight end play of the pump shaft assembly mentioned above is necessary in order to allow for the different rates of thermal expansion of the pump shaft and the pump body and the 75 differences in expansion resulting from one heat-

ing up faster than the other after the engine is started. In pumps of this general type but without the groove 5d, the provision of the necessary end play might occasionally cause trouble as follows: In a pump without the annular groove 5d within the impeller hub counterbore, the thrust washer would rest against a shoulder joining the cylindrical walls of the two parts of the recess. When the pump and fan were at rest or operating slowly, dirt in the cooling water would get into the clearance between the thrust washer and the shoulder. When the pump and fan would be speeded up and the pull of the fan would move the pump shaft assembly forward the dirt would prevent the washer from seating squarely on the shoulder. A particle of dirt at one side would tip the washer so that one side of it would not touch the end of the bearing bushing and water could easily leak out through the bearing. This leakage and consequent loss of coolant would occur at high speeds but seldom at idling speed or when the engine was not running, and hence in service it would often be difficult to locate the cause of the loss of coolant. Moreover, this defect would result in uneven wear on the back of the bearing bushing requiring frequent replacements.

In accordance with the present invention, however, any dirt or particle of foreign matter lodging between the thrust washer 11 and the shoulder 5e on the impeller hub is thrown out into the groove 5d and away from the shoulder 5e by centrifugal force as soon as the pump starts, as shown in Figure 4, and eventually escapes through one of the impeller hub slots 5f into the main stream of coolant.

Thus, considered from one of its broader aspects, our invention contemplates providing improved sealing means for a packless shaft subjected in operation to axial thrust, said means adapted both to seal such shaft against fluid leakage and to receive the axial thrust to which said shaft may be subjected. More particularly our invention contemplates providing improved sealing means for the shaft for a motor vehicle pump, which sealing means are adapted both to seal the shaft in the pump housing against leakage of the coolant and, in addition, to take up the end thrust or pull to which said shaft may be subject in operation, such as is the case when the fan is mounted on the pump shaft or when the pump impeller is of such a character that it exerts both radial and axial loads on the pump shaft. In addition, means are provided to collect and to dispose of the dirt and rust which the coolant may contain, thus eliminating the troubles which are caused by the presence of such impurities.

We claim:

1. In combination, a driven shaft having means exerting axial thrust thereon in one direction at predetermined times, a fluid impeller having a hub secured to said shaft, said hub having a bore concentric with said shaft, a fixed bearing within which the shaft is journaled and having an end vertical abutment wall between the impeller and said means, a thrust washer received within the bore of the hub movable axially on said shaft and connected for rotation therewith; said hub having an annular abutment movable axially into engagement with one face of said washer, when said means exerts axial thrust of predetermined magnitude on the shaft, to maintain said washer in sealing engagement with said abutment wall; and spring means opposing said axial thrust and effective to maintain said washer and abut-

ment wall in sealing engagement when the effort of said spring means exceeds said axial thrust, or when such thrust is absent, thereby effecting axial movement of said annular abutment away from said washer, said hub having an annular trough of greater diameter than the bore of the hub and of greater width than the thickness of the thrust washer facing the edge of said washer, said trough having an outlet into the fluid stream for the discharge by centrifugal action of particles collecting in said trough.

2. In combination, a driven shaft having means exerting axial thrust thereon in one direction at predetermined times, a fluid impeller having a hub secured to said shaft, a fixed bearing within which the shaft is journalled and having an end vertical abutment wall between the impeller and said means, a thrust member on said shaft received within the impeller hub and movable axially of the shaft relatively thereto; said hub having an abutment movable axially into engagement with one face of said thrust member, when said means exerts axial thrust on the shaft, to force said thrust member into sealing engagement with said abutment wall; and spring means for maintaining said thrust member in sealing engagement with said abutment wall when said axial thrust is removed or relieved to a predetermined extent, said hub having an annular trough with inward radial side walls facing the edge of said thrust member and an outlet into the fluid stream for the discharge by centrifugal action of particles collecting in said trough.

3. In combination, a driven shaft having means exerting axial thrust thereon in one direction at predetermined times, a fluid impeller having a hub secured to said shaft, a fixed bearing within which the shaft is journalled and having an end vertical abutment wall between the impeller and said means, a thrust member on said shaft movable axially of the shaft relatively thereto; said hub having an abutment movable axially into engagement with one face of said thrust member, when said means exerts axial thrust on the shaft, to force said thrust member into sealing engagement with said abutment wall; and spring means

for maintaining said thrust member in sealing engagement with said abutment wall when said axial thrust is removed or relieved to a predetermined extent, said hub having an annular trough with inward radial side walls facing the edge of said thrust member and an outlet into the fluid stream for the discharge by centrifugal action of particles collecting in said trough, said abutment of the hub forming one upright side wall of the trough.

4. In combination, a driven shaft movable axially at predetermined times by reason of end thrust, a fixed bearing for said shaft having a sealing wall, a fluid impeller having a hub secured to the shaft, a sealing washer rotatably connected to the hub but movable axially relative thereto into sealing engagement with said sealing wall, said hub having a trough with inward radial side walls facing the edge of the washer and an outlet into the fluid stream for the discharge by centrifugal action of particles collecting in said trough, one side wall of the trough forming an annular abutment movable axially into and out of engagement with the washer when end thrust in opposite directions is applied to the shaft.

5. In a water pump for an engine having a driven fan shaft subjected in operation to axial thrust, an impeller provided with a hub secured to the shaft, a fixed bearing within which said shaft is journalled, a thrust member on said shaft received within said impeller hub and rotatable therewith, said hub having axial movement relative to said member and a portion adapted to engage one face of the member to transmit thrust in one direction to force said member into sealing engagement with said bearing, spring means for urging said member against said bearing to maintain a seal therebetween when said thrust is removed, an annular groove or channel in said hub adjacent the edge of said thrust member having an outlet substantially in its plane into the fluid stream for the discharge by centrifugal action of particles collecting in the groove.
